UNITED STATES PATENT OFFICE.

WILLIAM G. MAGEE, OF HUDSON, NEW YORK.

CHAIR.

SPECIFICATION forming part of Letters Patent No. 543,744, dated July 30, 1895.

Application filed September 13, 1894. Serial No. 522,933. (No model.)

To all whom it may concern:

Be it known that I, WILLIAM G. MAGEE, of Hudson, in the county of Columbia and State of New York, have invented a new and Improved Chair, of which the following is a full, clear, and exact description.

My invention relates to improvements in chairs, and particularly to invalid-chairs.

The object of my invention is to produce an extremely simple and comparatively inexpensive chair which combines the functions of an ordinary reclining-chair, a rocking-chair, and a wheeled chair, which is provided with very simple adjusting mechanism for shifting the position of the chair in relation to the wheels, which is also provided with simple devices for converting the chair from one form to another, and which is so constructed that the chair may be automatically converted from a reclining to a roller chair by simply moving the body and rocking the chair forward.

To these ends my invention consists of certain features of construction and combinations of parts, which will be hereinafter described and claimed.

Reference is to be had to the accompanying drawings, forming a part of this specification, in which similar figures of reference indicate corresponding parts in all the views.

Figure 1 is a side elevation of the chair embodying my invention, and Fig. 2 is a vertical section of the same, the chair in both views being shown resting on its wheels. Fig. 3 is a detail section, partly in elevation, of the locking means for holding the front end of the chair elevated.

The chair is provided with the usual seat 10, legs 11, rockers 12, and arms 13, and it also has the customary back 14, which is hinged to the seat, as shown at 15, and is connected with the arms by links 16, these being pivoted to the arms, as shown at 17, and provided with a series of holes 18 to receive fastening-pins 19, by which the links are secured to the chair-back, and by means of the pins and links the chair-back may be adjusted to any desired inclination.

The chair is provided on opposite sides with two large wheels 20, which are high enough to be easily reached and turned by the hand of a person sitting in the chair, and the axles

21 of these wheels are journaled in the front ends of levers 22, which are fulcrumed, as shown at 23, in suitable hangers 24, and extend backward behind the chair, so that by moving them up or down the wheels may be raised or lowered so as to permit the chair to rest on its rockers or ride on the wheels, as desired.

The hangers 24 are firmly secured to the chair-seat at opposite sides, and they have rearwardly and downwardly extending curved arms 25, which are provided with holes 26, 27, and 28 to receive pins 29, which project through the levers 22, and by adjusting the pins in the proper holes the wheels may be held at any necessary height in relation to the chair-body.

The chair is provided with a third wheel 30, which is centrally arranged and is placed behind the chair and between the rockers 12, this wheel being substantially like the ordinary caster-wheel and having a vertical shank 31 which is pivoted in the rear end of an adjusting lever 32, and this is fulcrumed on a hanger 33 beneath the chair-seat 10, and the front end of the lever is adapted to engage a spring-bolt 34 which is inclined on the under side, as shown in Fig. 2, so that when the front end of the lever swings upward it will slide over the spring-bolt which, by engaging the under side of the lever, prevents it from accidentally returning. The spring-bolt 34, by holding the front end of the lever in a raised position, holds the rear end in a depressed position and thus keeps the caster-wheel 30 on the floor, so that it will prevent the chair from tipping back. The front end of the lever 32 moves between guides 35 on the chair-seat and this prevents the lever from swaying laterally. Means may be provided for turning the caster-wheel to the right or left so as to steer the chair, any usual device being employed, although I have shown nothing for the purpose. It will be seen that by bringing the main wheels to a bearing on the floor the front ends of the rockers will be elevated. When in this position the occupant of the chair may rock forward, thus lifting the back of the chair, and the rear end of the lever 32 will then drop, carrying the front end of the lever above the spring-bolt 34, and so the chair is in this way

automatically changed from a rocking or reclining into a roller chair.

The spring-bolt 34 is connected by a rod 37 with the lower arm 38 of a double lever, 5 which is fulcrumed on the chair-seat, and the upper arm 39 of the lever connects by a rod 40 with a bell-crank 41, which is journaled on a suitable support at one side of the chair-seat and is connected with a pull- 10 rod 42 which slides in a guide 43 on the chair-arm and terminates in a handle 44. By pulling up the handle 44 the rod 42 is raised, the levers 41, 38, and 39 tilted, and the spring-bolt pulled out so as to permit the front end 15 of the lever 32 to drop, and the chair is thus converted into a reclining or rocking-chair, as the case may be.

If the chair is to be used as a reclining-chair, the caster-wheel 30 is raised, the chair 20 arranged to rest on its rockers, and after the chair is tilted back to the desired position a rod 45 on one of the front legs is pushed downward so as to hold the chair in the desired position. This rod extends downward 25 through the leg and has at the bottom a foot 46 to rest on the floor, and when the rod is raised this foot rests in a socket 46^a in one of the rockers 12.

The rod 45 is locked either down or up by 30 a bolt 47 which projects into the chair-leg, and this is worked by a bell-crank 48, pivoted on one side of the chair-seat and held by a spring 49, so as to throw the bolt normally into engagement with the rod, and the bell- 35 crank may be tilted so as to release the bolt by a pull-rod 50, which works in a guide 51 on one of the chair-arms, this being shown by dotted lines in Fig. 1, and the rod has a suitable handle 52 at the top, which may be conveniently grasped.

Having thus described my invention, I claim as new and desire to secure by Letters Patent—

1. As an improvement in rocking chairs, the 45 combination with a rocker frame having arm rests and one of its legs formed with a verti-

cal guide portion, of a rod vertically movable on such guide portion having an operating handle projected above the side arm, and a foot portion adapted to be projected below 50 the rocker, and a locking device located adjacent the seat, having an upwardly projecting operating member, and having a latch adapted to be moved into engagement with the aforesaid rod, substantially as and for the 55 purpose described.

2. A chair of the kind described, comprising a rocking chair having pivoted and adjustable lever arms at the sides having main wheels journaled thereon, a latch mechanism and a 60 pivoted lever carrying a caster wheel at the rear end and having its front end projected and arranged to automatically lock in engagement with the aforesaid latch when the chair rests on the wheels and the body is tilted forward, substantially as shown and described.

3. The combination, with the rocking chair and its vertically adjustable side wheels, of the centrally arranged lever fulcrumed beneath the chair seat, the rear wheel on the 70 lever, and a locking device to engage the front end of the lever, this being automatically locked at the forward rocking of the chair, substantially as described.

4. The combination with a rocking chair, 75 having adjustable bearing wheels journaled thereon and a lock mechanism arranged under the seat of the chair, of a lever pivoted centrally under the chair, a caster wheel journaled on the rear end thereof, a guide for the 80 front end of the lever to hold it from lateral movement, said front end having a lock portion adapted to automatically engage the lock mechanism as the chair is tilted forward and hand operated releasing devices connected 85 with such lock mechanism, all arranged substantially as and for the purposes described.

WILLIAM G. MAGEE.
